DESIGN FOR A COMBINED PERFUME BOTTLE AND STAND THEREFOR

Arthur R. Botham, New York, N. Y., assignor to Coty, Inc., a corporation of Delaware

Application April 15, 1943, Serial No. 109,970

Term of patent 7 years

To all whom it may concern:

Be it known that I, Arthur R. Botham, a citizen of the United States, residing in the city, county, and State of New York, have invented a new, original, and ornamental Design for a Combined Perfume Bottle and Stand Therefor, of which the following is a specification, reference being made to the accompanying drawing, forming a part thereof.

Fig. 1 is a front elevational view of a combined perfume bottle and stand therefor, showing my new design;

Fig. 2 is a side elevational view;

Fig. 3 is a top plan view;

Fig. 4 is a perspective view thereof.

The dominant features of my design reside in the portions shown in full lines.

I claim:

The ornamental design for a combined perfume bottle and stand therefor, substantially as shown and described.

ARTHUR R. BOTHAM.
